UNITED STATES PATENT OFFICE.

ALVARO MULLOR, OF SCEAUX, FRANCE, AND LOUIS CARRIOL, OF GHENT, BELGIUM.

WEFT-FEEDING DEVICE FOR WEAVING LOOMS.

Application filed March 23, 1926, Serial No. 96,873, and in France March 23, 1925.

This invention relates to weft feeding devices for looms and it has for its object to provide a device of this kind in which the weft is continuously fed in loop form without requiring the shuttle to be stopped before it reaches the end of its travel in either direction. Another object is to provide suitable means for tensioning the weft threads passed through the shed and further objects will be apparent from the following description.

According to our invention we provide on the one hand a thread-carrier on the shuttle and on the other hand we arrange at the entrance of each shuttle box a thread-presenting guide and an oscillating thread-gripping hook, arrangement being such that, on each travel in the same direction of the shuttle, the thread fed from the supply bobbin through said guide to the nearest selvedge, is caught by the thread-carrier on the shuttle, carried thereby through the shed and delivered to the oscillating hook which lays it in loop form at the other selvedge.

In carrying out our invention we preferably use a shuttle of ordinary design having a portion cut away on its upper side and provided at each end with a fork-shaped thread-gripping member. These members have their thread-gripping faces turned inwardly so that in either direction of travel the thread will be seized by the rear fork.

On each side of the loom is a supply bobbin from which the weft thread is led to the selvedge through the guide which holds it across the path of the forks on the shuttle. The weft thread being seized by the rear fork is carried through the shed and, as it reaches the other end, it is caught by the oscillating hook which is lowered between the tines of the fork, disengages the thread from the fork and drops it in loop form at the selvedge as the lay is being actuated.

Means are preferably provided for tensioning the loop or weft. To this end, as the shuttle enters the shuttle box it acts through suitable connections on a brake at the feeding end of the weft thread which is thus tensioned at the very moment a tightening of the loop is required. The brake may also be controlled by cam action but in that case it has been found that the thread is liable to break owing to undue stretching, whereas when the braking action is timed by the shuttle itself such accident is entirely precluded.

In order that our invention may be better understood we shall describe an embodiment thereof with reference to the accompanying drawings in which:

Fig. 1 shows a side elevation of a loom provided with our improved weft feeding device.

Figs. 2 and 3 are respectively a plan and an elevation of the shuttle on an enlarged scale, Fig. 4 being an enlarged cross-section on line A—B of Fig. 2.

Figs. 5 and 6 show separately one of the forks of the shuttle in front and side elevation.

Fig. 7 is a diagrammatic plan view of the shuttle race.

Figs. 8, 9 and 10 respectively show a plan view, a side elevation and an end view of the left hand shuttle box, the picker being removed in Fig. 10.

Fig. 11 is a side view of the thread-presenting hook.

Figs. 12, 13 and 14 illustrate the engagement of the thread by the oscillating hook.

Figs. 15, 16, 17 and 18 illustrate the positioning of the loop at the selvedge by means of the oscillating hook.

Fig. 19 is a side view of the cam controlling the operation of the thread-gripping hook.

Figs. 20 and 21 are a side view and a sectional view of the brake for tensioning the weft thread.

Referring to Fig. 1, 20 denotes the loom frame, 21 the main shaft, 22 the cam shaft, 23 the lay and 24 the lay swords pivoted at 25 and operated by shaft 21 through the cranks 26 and links 27. *a* is the warp controlled in the usual manner by the healds 28 and *b* is the weft fed at each side from a bobbin 29 located on the floor or on any suitable support.

The shuttle 30 is cut away on the top and provided at each end with a fork 31 (Figs. 2 to 6) secured thereto by means of a pin 32. The tines of the forks 32 have an inclined top face 33 and a thread-engaging recess 34, these recesses being turned inwardly, i. e. facing each other, as shown in Fig. 2.

At the entrance of each shuttle box 35 (Fig. 7) are the thread-presenting means 36, 37 for co-operating with the shuttle as it is shot outwards, and the oscillating thread-gripping hook 38 for co-operating with the shuttle as it flies into the box.

The thread-presenting means comprise an

eye 36 on a rod 39, and a hook 37 secured to the rail 40 on the lay 23 (Figs. 8 to 10). The weft thread *b* extending from the bobbin 29 to the selvedge 70 (Fig. 7) passes through the eye 36 and thence under the hook 37 whereby it is held across the path of the forks 31 on the shuttle. Owing to the incline 33 at the top of the forks, the thread will slide over the front fork but it will be caught and carried away in loop form by the recess 34 in the rear fork on the shuttle being shot outwards. The rod 39 is pivoted to the frame at 41 (Fig. 1) and actuated by the cam shaft 22 through the link 42 and the roller 43 on the cam arm 44, the movement of the rod 39 being intended to lift the weft thread out of the path of the thread-engaging forks when the shuttle flies in.

The oscillating hook 38 (Figs. 8 to 10) is mounted axially of the shuttle on a shaft 45 mounted in bearings 76 on the rail 40. To the shaft 45 is secured an arm 46 connected to a rod 47 pivoted at 48 (Fig. 1) to an oscillating lever 49. This lever is pivoted at one end to the frame at 50 and it carries at its other end a roller 51 riding on a cam 52 secured to the cam shaft 22. As shown in Figs. 12 to 18 the hook 38 is provided with a wedge-shaped tail piece 53 for the purpose of assisting the hook in picking up the weft thread from the fork 31 as will be explained hereinafter.

On its way from the bobbin 29 to the thread-presenting means 36, 37 the weft thread passes between the jaws 54, 55 of a brake actuated by the shuttle as it reaches the far end of the race in order to secure the desired tensioning of the weft. To this end we utilize, in the example illustrated, the shaft 56 of an automatic stop mechanism of current design, which is mounted in bearings 66 in the lay-swords 24. This shaft is held by the spring 57 in such position that a dog 58 on said shaft is adapted to strike against an abutment 59 (Fig. 1) and stop the operation of the lay swords when the shuttle fails to reach the shuttle-box. When the shuttle operates normally, it moves the box swell 60 on entering the shuttle box (Figs. 8 to 10) and thus causes the lever 61 to rock the shaft 56 and lift the dog 58 out of the path of the stop 59, as is well known.

For the purposes of the present invention the shaft 56 is extended at both ends under the shuttle boxes 35, and to each end of shaft 56 is secured an arm 62 connected by links 63, 64 to a spindle 65 on which is secured the brake jaw 55 (Figs. 10, 20, 21). The brake jaw 54 is stationary and secured to a frame 67 secured to the lay by means of an arm 75 and having eyelets 68, 69 for guiding the weft thread *b*. The brakes at both ends of the shuttle race are actuated at the same time, but only one is operative, i. e. the thread is tensioned by the right-hand brake

when the shuttle enters the left-hand box and vice-versa.

When the loom is not provided with a stop motion mechanism of the kind described, a rock shaft such as 56 can easily be fitted under the lay and shuttle boxes.

The operation is as follows:

When the shuttle is shot by the picker 71, the rear fork 31 seizes the thread *b* presented by the hook 37 and carries it in loop form through the shed. As the shuttle reaches the selvedge at the other end of the shed it passes under the oscillating thread-gripping hook 38 which at this moment stands in the position of Fig. 12. The hook being centrally positioned in the path of the forks 31, the fork tines will pass on either side of it and the wedge-shaped tail-piece 53 will engage beneath the portion of the thread *b* extending across the two tines of the rear fork 31 (Fig. 13). The shuttle continuing its motion the thread is raised by the tail 53 which picks it off the fork and drops it into the rearwardly curved hook 38 (Fig. 14).

As the lay advances to beat up the weft the hook 38 swinging on its pivot 45 in the direction of the arrow (Fig. 15), carries the end of the loop to the selvedge (Fig. 16). The lay continuing to advance, the hook 38 is then swung in the opposite direction (Fig. 17), drops the end of the loop at the selvedge 70 and resumes its inoperative position shown in Fig. 18. In order successively to impart to the thread-gripping hook 38 two different oscillating movements the cam 52 (Fig. 19) has two cam portions 72, 73 for controlling the operation of the hook and holding it in its position of rest.

Meanwhile, as the shuttle reaches the end of its travel and enters the shuttle box it moves the box swell 60 about its pivot 74 (Fig. 8) and through the medium of the arm 61 it causes the abutment shaft 56 to turn slightly in the direction of the arrow (Fig. 10). By means of the arm 62 and links 63, 64, this movement is transmitted to the spindle 65 which moves the brake jaw 55 towards the jaw 54 and grips the thread *b*. While, as stated before, the shaft 56 actuates at the same time the brakes of the two shuttle boxes, in the position illustrated in Figs. 8 to 10 (with the shuttle within the left-hand box) it is obviously the operation of the right-hand box brake that puts under tension the loop just transferred from the shuttle to the left-hand hook 38. By thus placing the operation of the brake under the control of the shuttle itself, we are able to time exactly the tensioning of the weft and avoid any undue stretching and breakage of the loop.

When the shuttle is shot out of the box 35 the box swell 60 and shaft 56 resume their initial positions under the action of the spring 57 and the released brakes permit the free passage of the thread. The braking ac-

tion may be varied as required, for example by varying the angular position of the arm 61 on the shaft 56 or in any other suitable manner.

5 It is obvious that changes may be made in the arrangement of the thread-engaging means on the shuttle and in the shape of the co-operating means on the lay without departing from the scope of the appended 10 claims.

We claim:

1. In a loom, the combination of a lay, a weft supply, a shuttle on said lay, a fork-shaped thread-carrier on said shuttle having 15 its tines in a plane extending transversely of the shuttle, thread-presenting means on said lay, a downwardly extending thread-gripping member on said lay for picking up the weft thread from said thread-carrier, and 20 means for causing said thread-gripping member to drop the weft thread at the selvedge.

2. In a loom, the combination of a lay, a weft supply, a shuttle on said lay, thread-engaging means on said shuttle, means for presenting the weft thread to said thread-engaging means, and an oscillating member on the lay for picking up the weft from said 25 thread-engaging means and dropping it in 30 loop form at the selvedge.

3. In a loom, the combination of a lay, a weft supply, a shuttle on said lay, a thread-engaging fork on said shuttle, means for presenting the weft thread across said fork, 35 and a thread-gripping hook pivotally arranged on the lay centrally of the path of said fork and adapted to pick up the thread therefrom.

4. In a loom, the combination of a lay, a weft supply at each end of said lay, shuttle boxes and a shuttle on said lay, a thread-carrier on said shuttle, means at the entrance of each shuttle box respectively for presenting the thread to said thread-carrier on the 40 shuttle flying out and for picking up the thread from said thread-carrier on the shuttle flying in, means for controlling the operation of said thread-presenting and of said thread-picking up means, means for tensioning the thread from each weft supply, and means controlled by said shuttle for operating said tensioning means.

5. In a loom, the combination of a lay, a

shuttle on said lay, a pair of upstanding forks secured each to one end of said shuttle, 55 the tines of said forks having an outwardly sloping top face and an inwardly turned thread-engaging recess, and thread-gripping means on said lay adapted to co-operate with said forks.

6. In a loom, the combination of a lay, a shuttle on said lay, a thread-engaging fork on said shuttle, a thread gripping hook pivoted to said lay and located centrally of the path of said fork, and means for rocking 60 said hook.

7. In a loom, the combination of a lay, a shuttle on said lay, a thread-engaging fork on said shuttle, a thread gripping member pivoted to said lay and located centrally of 70 the path of said fork, said member comprising a hook and a wedge-shaped tail piece adapted to pass between the tines of said fork, and cam-controlled means for alternately swinging said member through different angles.

8. In a loom, the combination of a lay, a weft supply, a shuttle on said lay, a thread-carrier on said shuttle, means for presenting the weft thread to said thread carrier, means 80 on said lay for picking up the thread from said thread-carrier, and means between said weft supply and said thread-presenting means for braking the weft thread.

9. In a loom, the combination of a lay, a weft supply, a shuttle on said lay, a thread-carrier on said shuttle, means for presenting the weft thread to said thread-carrier, means 85 for removing the thread from said thread-carrier, and means controlled by said shuttle for braking the weft thread.

10. In a loom, the combination of a lay, a weft supply, shuttle boxes and a shuttle on said lay, a rock shaft extending below said lay and shuttle boxes, means in each shuttle 95 box for controlling the motion of said shaft, said means being controlled by said shuttle, a thread-carrier on said shuttle, thread-presenting and thread-gripping means on said lay for co-operating with said thread-carrier, and thread-braking means controlled 100 by said shaft.

In testimony whereof we affix our signatures.

ALVARO MULLOR.
LOUIS CARRIOL.
